CASHIER'S SHIELD

William Cain, Sr., Newburg, W. Va.

Application January 18, 1934, Serial No. 707,181

4 Claims. (Cl. 20—1.01)

This invention relates to cashiers' shields, and more particularly to an apparatus which can be readily installed in front of cashiers' cages for protection against "hold-ups" and it consists in 5 the constructions, arrangements and combination herein described and claimed.

It is a particular object of the invention to provide spring actuated closure means for the windows, with latch means for normally holding the 10 closure in open position, and treadle means operable by the tellers or other persons for releasing the latch mean to permit the closure to close the window opening and thus prevent the burglars from having access to the money within the teller's cage.

It is also an object of the invention to provide a novel means for positively locking the closure means in its operative position before the teller's window, as well as providing means for returning 20 the closure means to normal position.

The invention is well adapted for use in banks and other commercial houses where the cashier's cage is more or less exposed to burglary, and in order that the invention may be fully understood, 25 reference is now made to the accompanying drawings forming a part of this application, wherein,

Figure 1 is a front elevation of a cashier's cage provided with my invention,

Fig. 2 is a top plan view, the top panel being 30 moved,

Fig. 3 is an end elevation of the cage, the end panel having been removed,

Fig. 4 is a rear elevation of the cage, illustrating the treadle operating means, the rear panel having been removed,

Fig. 5 is a cross section on the line 5—5 of Fig. 4.

Fig. 6 is a vertical section on the line 6—6 of Fig. 4.

Referring to the drawings in detail, the reference character 10 represents the partition which separates the tellers of a bank or the like from the patrons, and as customary, includes window openings 11 through which business transactions 45 are conducted. Ordinarily, when a "hold-up" is attempted, it is through these windows, and it is therefore a purpose of my invention to provide a spring-projected slidable steel plate before the teller's cage, thereby fully protecting the money 50 and the teller from the hold-up men.

The partition 10 is suitably built into a frame structure, generally indicated at 12, which includes hollow end posts 13 connected by spaced panel members 14 and 14a at the base of the frame. The posts 13 at their top portions are

connected by a box member 15 as clearly shown in Figs. 2 and 6. The box 15 provides a channel 16 for housing a portion of the operating mechanism, as will be described.

Any suitable base 17 may be provided for the 5 frame work and connects the panel members 14—14a and corner posts 13 thereby affording rigidity to the structure. It will be noted that the panels 14—14a stop approximately midway of the height of the frame structure and the upper edge portions support a counter 18. The counter 18 in the present instance is shown as formed of two separate members 18a and 18b, their adjacent parallel edges being spaced as at 19, providing a passageway for the sliding closure 20.

The inner vertical side members 21 of the corner posts 13 are slotted as at 22, of a length to accommodate sliding movements of the shutter 20 as will be more clearly apparent as the description proceeds. Guide strips 23 are secured to the side members 21, arranged upon opposite sides of respective slots 22. The guide strips 23 therefore define a channel-way 24 through which the closure 20 may slide during its operative movements.

Attention is now directed to Figs. 2, 3, and 6 for a discussion of the operating means for the shutter 20. Within the channel 16, at the center thereof, a shaft 25 is suitably journaled, one end of which projects through the boxing 15 upon one side thereof, and upon the projecting portion of the shaft there is secured a hand lever 26, whereby rotary movement may be imparted to the shaft 25. Disposed within the channel 16 and keyed to the shaft 25 there is a drum generally indicated at 27, which comprises a pair of integrally connected drum members 28 and 29.

Immediately above each corner post 13 and positioned and secured within the channel 16, there is a frame 30 comprising side walls 31. The 40 frames 30 may be secured to the corner posts 13 and the base of the boxing 15, as illustrated in Figs. 2 and 3. The frame members 30 have an open end 32 disposed toward the drum 27 and between the side walls 31 there are revolvably 45 mounted upon a shaft 33, pulleys 34—34 and 34' and 35' respectively.

Upon the base 17 there are secured respective pulleys 36 and 37, these pulleys being positioned within the hollow corner posts 13, as clearly seen 50 in Fig. 5, and are aligned with respective slots 22.

A cable 38 is provided, one end thereof being secured to the pulley 28, from whence it passes around the pulley 34, thence downwardly through one corner post 13, guided by an eyelet 39, passes 55

partially around the pulley 36 and then secured to the eyelet 40 fixed to the lower edge of the closure 20 (see Fig. 5). A helical spring 41 is also anchored by the eyelet 40, and extends from its anchorage upwardly over the pulley 35, and is finally made secure to the frame 30 at the opposite side of the main frame 12, as indicated at 42. A similar cable 43 is secured, at one end to the pulley 29, the opposite end of the cable being passed around the pulley 35' and thence through the eyelet 39', partly around the pulley 37 and finally secured to the eyelet 40' carried by the lower portion of the closure 20. A helical spring 44 is also anchored to the eyelet 40' and extends upwardly over the pulley 34' and is finally anchored as at 42' to the frame 31 disposed at the opposite side of the main frame 12.

The cables 38 and 43 are wound upon the drums 28 and 29 in the same direction, so that upon rotation of the shaft 25, by manipulation of the handle 26, the closure 20 will be moved downwardly to position the same below the counter 18.

The closure 20 is normally retained in its lowermost position, as indicated in Fig. 6, and in such position it will be apparent that the springs 41 and 44 are under tension, tending to draw the closure 20 to its closed (raised) position, but the closure is held against such movement until it is desired to release the same, by a trigger 45. The trigger 45 comprises a body portion 46 of a length stopping slightly below the counter 18 and terminates in a bill member 47 adapted to engage within an opening 48 formed in the closure 20, adjacent its upper edge. An elongated slot 49 is formed in the body portion 46 adjacent its lower edge, the slot being disposed at a slight angle with respect to the lower edge of the trigger and within this slot there is positioned a crank portion 50 of a foot treadle 51. In order that the trigger 45 shall always be in a position to cause engagement of the bill 47 within the opening 48, a suitable leaf spring 52 is secured between the base 17 and the trigger body 46, in such position to cause the trigger to swing inwardly toward the closure.

In the present instance, I have illustrated a "cage" structure embodying four cashiers' windows, and a single closure 20 is employed operable to close all windows simultaneously, by any one of the cashiers. This is brought about by provision of a single foot treadle 51, previously referred to. The treadle is suitably mounted upon the base 17 by bearings 53 and includes four pedal members 54, one positioned adjacent or directly beneath each cashier's window.

The operation will be readily understood from the following discussion.

It will be assumed that the closure 20 is in its lowered or set position, placing the springs 41-44 under tension. If a burglar should appear before any of the windows 11, any of the cashiers or tellers would simply depress his pedal 54 with his foot. Such movement of the pedal would swing the trigger 45 backwardly away from the closure 20, against the tension of the spring 52, with consequent withdrawal of the bill 47 from the opening 48. The springs 41-44 would then immediately function to quickly project the closure 20 upwardly before the windows 11, thus separating the burglar from the tellers, and since the closures 20, in practice will be steel, the possibility of shooting through the closure is not possible.

As soon as the closure 20 is sprung upwardly, the spring 52 will swing the trigger to its normal

position, as soon as the operator's foot is removed from the treadle, placing the bill 47 beneath the closure, thus preventing downward movement of the closure. In order to return the closure to its set position, one of the foot pedals 54 is depressed so as to swing the trigger outwardly and the hand lever 26 is then rotated. Such rotation of the handle and its associated shaft will cause rotation of the pulleys 28 and 29 causing the cables 38 and 43 to be wound up thereon. The shortening of the cables in this manner, it will be seen, draws downwardly upon the closure 20. After the closure 20 has passed slightly downwardly into the slot 19, the pedal may be released, and as soon as the bill 47 aligns with the opening 48, it will spring thereinto, securing the closure in readiness for its next operation.

Obviously, an electrical alarm system may be readily installed in the cage, the circuit of which is completed upon closing of the closure 20, to sound an alarm exteriorly of the building.

While I have shown and described a preferred embodiment of the invention, it should be understood that I do not confine myself to the exact construction set forth, and reserve as my own all such modifications as fairly fall within the scope of the appended claims.

I claim:

1. A cashier's cage having tellers' windows and a trough, hollow corner posts in communication with the trough, a pair of drum members revolvably mounted within the trough, crank means for revolving the drum members, dual pulley members mounted within the trough immediately above each corner post, a guide pulley mounted within each corner post aligned with respective dual pulley members, each corner post having a vertically disposed guide-way and slot positioned in opposed relationship to one another, a closure positioned within the opposed guide-ways, an eyelet formed on the vertical edges of the closure and extending through respective slots, a cable member connected to each respective eyelet, each cable being passed partially around respective guide pulleys and thence around one of the dual pulleys and wound in the same direction upon respective drum members, a pair of retracting springs within the trough, the end of one spring being anchored to one end of the trough and one end of the other spring being anchored at the opposite end of the trough, and being trained around the other of the respective dual pulleys, the other end of the spring members being secured to respective eyelets, trigger means for holding said closure against retraction by said springs and treadle means for releasing the trigger.

2. A cashier's cage having one or more windows, a closure slidably behind said windows, a trough above said windows, hollow corner posts in communication with the trough, a pair of drum members revolvably mounted within the trough, crank means for revolving the drum, dual pulley members mounted within the trough immediately above each corner post, a guide pulley mounted within each corner post in line with the dual pulley members, each corner post having a vertically disposed guide-way and slot positioned rearwardly of the windows, a closure positioned within the opposed guide-ways, an eyelet formed on the vertical edges of the closure and extending through respective slots, a cable member connected to each respective eyelet, each cable being passed partially around respective guide pulleys and thence around one of the dual pulleys.

and wound in the same direction upon respective drum members, a pair of retracting springs within the trough the end of one spring being anchored to one end of the trough and one end 5 of the other spring being anchored at the opposite end of the trough, each spring further being trained around the other of the respective dual pulleys, the other end of the spring members being secured to respective eyelets, a treadle mounted on the floor of the cage, said treadle having a crank member, a trigger mounted upon the crank, said trigger having a bill member engageable with the closure to hold the same against the tension of the retracting springs, and spring 10 means normally urging the trigger toward the closure.

3. A cashier's cage having a window, a foot treadle behind the window, a closure slidable behind the window, retracting springs to raise the 15 closure, a trigger operably associated with the

treadle of a length stopping slightly below the base of the window, said closure having an aperture adjacent its upper horizontal edge, and said trigger having a bill projectable into the aperture in one position of the closure and into the 5 path of downward movement of the closure.

4. A cashier's cage having a window, a foot treadle behind the window, a closure slidable behind the window, retracting springs to raise the 10 closure, a trigger operably associated with the treadle of a length stopping slightly below the base of the window, said closure having an aperture adjacent its upper edge, the trigger having a bill projectable into the aperture in one position of the closure and into the path of downward movement of the closure after release of the bill from the aperture, and means for lowering 15 said closure to normal set position after retraction of said trigger.

WILLIAM CAIN, SR. 20
